TELEPHONE SYSTEM

Edward S. Peterson, Elmwood Park, Ill., assignor
to Associated Electric Laboratories, Inc., Chi-
cago, Ill., a corporation of Delaware

Application December 10, 1937, Serial No. 179,124

23 Claims. (Cl. 179—1)

The present invention relates generally to signalling systems and has for one of its objects the provision of an improved telephone system adapted for use on a train comprising a plurality of 5 cars or vehicles.

The utility of providing telephone facilities on a railway train for communication between the various cars has been recognized for some time and, as a result, telephone apparatus has been 10 provided as standard equipment in the construction of the railway cars of recent design. One of the chief points of utility in providing a system of this character is that of enabling the engineer in the locomotive cab to be advised by members 15 of the train crew as to the condition of the train from telephone stations located at strategic points in certain of the cars of the train. Specifically, the greatest use is found in switching operations wherein a train attendant may relay information over the telephone system to the locomotive engineer from a telephone station located at the rear of the rear car, thereby to control movement of the train in a rearward direction. As is well known, it is frequently necessary to provide 20 two locomotives on trains which are heavily loaded and which are required to travel over routes having highly graded roadbeds. In this type of train, it is highly desirable that telephone equipment be provided such that communication 25 may be had between the two locomotive cabs and between each of the cabs and other telephone stations located in the other cars of the train. Trains are usually made up by the train crew prior to each run and no set rule is followed as regards 30 the particular cars which will make up the train in any given case or the manner in which these cars will be arranged. This is particularly true with reference to the manner in which the two locomotives of a double-header train are connected for use. By virtue of this indiscriminate mode of assembling the cars making up a 35 train, the problem is raised of providing a telephone system wherein the telephone stations may be connected in a variety of ways to form a unified system and wherein the mode of operation of the system is the same irrespective of the arrangement of the component stations.

It is a further object of the present invention, therefore, to provide an improved and exceeding- 40 ly simple arrangement whereby communication facilities are provided between the cab of either of two locomotives of a double-header train and other telephones located in the other cars of the train, and also directly between the two cabs, and 45 wherein the apparatus in each cab is so arranged

that the locomotives may be disposed in any desired order without disturbing the communication facilities.

More specifically, it is an object of the invention to provide telephone equipment of improved and economical arrangement for use on a vehicle, such, for example, as a locomotive cab, which may be connected in a telephone system in any one of a number of ways to provide communication facilities for the vehicle and wherein the mode of 5 operating the equipment is the same irrespective of the manner in which the equipment is connected in the system.

In the specific embodiment of the invention described hereinafter, there are provided a plurality of telephone stations respectively located on certain of the several vehicles making up a railroad train, which stations are interconnected by a line circuit comprising a plurality of conductors. Two telephone stations are located in 20 each of the two locomotive cabs embodied in the train and one station is provided in each of certain of the other cars equipped for telephone service. The equipment at each station comprises a telephone transmitter and receiver normally disconnected from the line circuit and a manually operable switch operative to connect the associated transmitter and receiver to the circuit. Since the primary purpose of the system is to provide 25 facilities for transmitting information to the engineer, a signal device is only provided at one of the stations located in each of the locomotive cabs. The arrangement is such that the signal device provided at the one station in each cab may directly be energized through the operation of a manually operable switch provided at the other station located in the same cab over a 30 circuit independent of the line circuit, or it may be energized in response to the operation of a manually operable switch provided at one of the 35 stations located in the other locomotive cab. As regards the energization of the signal devices on calls initiated at stations other than the locomotive cab stations, means are provided responsive to the actuation of a manually operable switch 40 at one of these other stations for causing the simultaneous energization of all of the signal devices. When such a call is answered at one of the stations in one of the cabs, control apparatus is caused to operate to cause the deenergization of 45 all of the signal devices. By this arrangement the method of signalling is rendered selective as regards calls between the cab stations, but is non-selective on calls originating at a station other than a cab station.

The novel features believed to be characteristic of the invention are set forth with particularity in the appended claims. The invention, both as to its organization and method of operation, together with further objects and advantages thereof, will best be understood by reference to the specification taken in connection with the accompanying drawings, in which one embodiment is illustrated. In the drawings, Figure 1 illustrates the apparatus provided at the two telephone stations located in the cab of the first locomotive of a double-header train, Fig. 2 illustrates the similar apparatus provided at the two stations of a second locomotive, and Fig. 3 illustrates the apparatus provided, respectively, at two telephone stations located in two different cars of the train following the two locomotive cabs.

Referring now more particularly to the drawings, there is illustrated an improved telephone system which is particularly well suited for the application mentioned above, namely, on a train comprising a plurality of vehicles, at least certain of which, such, for example, as the locomotives, are interchangeable. In brief, the system comprises a plurality of telephone stations 100, 150, 200, 250, 300 and 350 interconnected by a line circuit divided into sections 104, 204, 304 and 307. As indicated in the drawings, the two stations 100 and 150 are located in the cab of the first locomotive of the train, the two stations 200 and 250 are located in the cab of the following or second locomotive of the train, the station 300 is located in the baggage car, and the station 350 is located at the rear of the rear car, which latter car may be the observation car of a passenger train or the caboose of a freight train. The enumerated sections of the line circuit extend between the several cars and terminate in voice frequency current repeaters. Thus, the line circuit section 104 comprises a pair of conductors 105 and 106, respectively connected to the terminals of one winding 191, 192 of a repeating coil 190 located in the first locomotive cab at the station 100. The conductors of this pair are also connected to the respective terminals of one winding 293, 294 of a repeating coil 290 located at the station 200 in the cab of the second locomotive. The other winding 193, 194 of the repeating coil 190 has its terminals connected, respectively, to the conductors 102 and 103 of the line circuit section 101, this section being open-circuited, as shown, with the locomotives arranged in tandem in the order indicated but being provided for use in the event the order of the locomotives is reversed. The repeating coil 290 includes a winding 291, 292 having its opposite terminals connected, respectively, to the conductors 205 and 206 of the line circuit section 204. These last-mentioned conductors also terminate at the respective terminals of one winding 343, 344 of the repeating coil 340 located at the station 300. The other winding 341, 342 of the coil 340 is arranged to be connected by the pair of conductors 305 and 306 to the winding 373, 374 of the repeating coil 370 located at the station 350. Finally, the other winding 371, 372 of the repeater 370 is connected by way of the pair of conductors 308 and 309 making up the line circuit section 307 to the opposite terminals of the telephone hand set located at the station 350.

Each of the telephone stations 100, 150, 200, 250, 300 and 350 comprises a transmitter and a receiver normally disconnected from the line

circuit and preferably in the form of a hand set, and a manually operable switch which is operative to cause the associated transmitter and receiver to be connected to the associated section of the line circuit. More specifically, there is provided at the rear car station 350 a hand set 360 comprising a receiver 361 and a transmitter 362. This hand set also has embodied therein a manually operable switch comprising the springs 364 and an actuating member in the form of a push button 363. Similarly, the apparatus at the station 300 comprises a hand set 330 having embodied therein a receiver 331 and a transmitter 332, together with a manually operable switch including the springs 334 which normally occupy the open-circuited position illustrated in the drawings but may be moved into engagement through the actuation of an associated push button 333. The last-mentioned station also includes a lockout relay 310 which forms means responsive to the operation of the switch in the hand set 360 for preventing the transmitter 331 and the receiver 332 from being connected to the terminals of the repeater winding 341, 342 when the line circuit is busy in connection with a call from the station 350 to one of the locomotive cab stations. It will be noted that the circuit arrangement of the apparatus located at the station 300 is slightly different from that of the apparatus provided at the station 350 in that the manually operable switch comprising the springs 334 is not effective directly to connect the associated transmitter and receiver to the conductors of the line circuit section 304, but rather is effective to complete the operating circuit for a second relay R320, which relay, in turn, performs the line switching functions. The relay R320 is also operative to prevent a call from being initiated at the station 350 when the line circuit is busy in connection with a call originated at the station 300.

The apparatus provided in each of the locomotive cabs is identical and, hence, it is believed that a brief description of the apparatus located in cab No. 1, as illustrated in Fig. 1, will suffice for the present, especially in view of the fact that the corresponding elements in cab No. 2, as illustrated in Fig. 2, are identified by the same reference numerals prefixed with the two hundreds digit rather than the one hundreds digit. As illustrated in Fig. 1, the apparatus in the first locomotive cab at the station 100 comprises a hand set 140 having embodied therein a receiver 141 and a transmitter 142 together with a manually operable switch comprising the springs 144 and the push button 143. Similarly, the apparatus at the station 150 comprises a hand set 170 including a receiver 171 and a transmitter 172 and having embodied therein a manually operable switch comprising the springs 174 which are under the control of a push button 173. This station also includes a device in the form of a relay R160 which operates in response to the actuation of the push button switch to connect the transmitter 172 and the receiver 171 across the conductors 105 and 106 of the line circuit section 104. Also included at the station 100 is a signal device in the form of a bell ringer 187 which comprises an operating magnet 189 and contact springs 188 under the control of the bell striker. This signal device includes an operating circuit which is independent of the line circuit and is arranged to be completed in response to the actuation of a push button switch 175 provided at the station 150. By this arrangement, a person

calling the station 100 from the station 150 may signal the first-named station directly and without affecting the signal device provided at the station 200. The signal device noted also includes 5 an alternative operating circuit, traced hereinafter, which is under the control of each of two relays R110 and R120. As will be pointed out in detail hereinafter, the relay R110, and also the corresponding relay R210 provided at the station 10 200, comprise means responsive to the operation of either of the two push button switches embodied in the apparatus at the station 300 and the station 350, respectively, for completing the alternative operating circuits for the signal devices 15 187 and 287 located, respectively, at the stations 100 and 200. The signal devices noted are deenergized, following their energization, through the provision of a relay R130 at the station 100 and a corresponding relay R230 at the 20 station 200, which relays are respectively arranged to respond to the actuation of the manually operable push button switch provided at the respective two stations or to the operation of the corresponding relay at the other station. 25

The alternative operating circuit for the signal device 187 may also be completed through the operation of the relay R120 but, with the cabs arranged in the order described above, this relay is not susceptible of being energized. At the station 200, however, the corresponding relay R220, which is arranged to complete the alternative operating circuit for the signal device 287, operates in response to the actuation of a second manually operable switch 180 provided at the station 100. The relay R130 provided at the station 100 not only functions to cause the signal device 187 to be deenergized under certain conditions, but is also operative to connect the transmitter 142 and the receiver 141 across the line conductors 105 and 106 of the line circuit section 104. Similar functions are performed by the corresponding relay R230 provided at the station 200. 30

Current for energizing the various relays indicated in the drawings and the two signal devices is obtained from a common source which, preferably, comprises the storage battery conventionally embodied as standard equipment in each of the locomotives. In order to facilitate a description of the circuits involved, this source has not been 35 illustrated in the drawings, but it is explained that the positive terminal of the source is connected to all circuit conductors indicated as terminating at ground whereas the negative terminal of the source is connected to the various negative terminals illustrated in the drawings. Since each of the transmitter and receiver cells embodied in the various hand sets may be of any standard commercial construction, these elements have been only schematically illustrated in 40 the drawings. It is pointed out, however, that each of the transmitters 142, 172, 242, 272, 332 and 362 is preferably of the self-powered type which obviates the necessity of using an auxiliary current source for voice frequency current transmission. Several well-known transmitters of this 45 type are commercially available. In brief, this type of transmitter usually comprises a diaphragm which is connected by means of a sturdy but very light connecting rod to an armature balanced between the poles of an extremely powerful permanent magnet. In its operation, and when sound waves impinge upon the diaphragm, the diaphragm vibrates in accordance with these waves to transmit the vibrations to the armature. 50 The armature, in turn, vibrates and sets up a

variation in the magnetic lines of force, both in number and direction, causing an induced alternating voltage to be developed in the coil windings forming a part of the magnetic field. The induced voltage thus generated varies in amplitude and frequency in accordance with the amplitude and intensity of the input sound waves. 5

As indicated above, with the arrangement described, it is only possible for the locomotive cab stations to be called. Referring now to the operation of the apparatus to complete a connection between the station 350 and one of the two stations 100 and 200, it is pointed out that the call is initiated in response to the actuation of the button 363 embodied in the hand set 360. 10 This results in the completion of a simplex circuit for energizing the lockout relay R310 provided at the station 300, one branch of this circuit extending from ground on the conductor 335 by way of the closed switch springs 364, the conductor 366, the winding 373, the conductor 305, RA313, RC314, RA323 and through the winding of R310 to battery, and the other branch extending from the conductor 366 by way of the winding 374, the line conductor 306, RA316, 15 RA317, and RA324 and through the winding of R310 to battery. The relay R310, upon operating, opens, at RA312', a point in the operating circuit for R320, thereby to prevent the transmitter 332 and the receiver 331 at the station 300 from being connected to the conductors of the line circuit in response to the operation of the push button 333. At its armatures RA312 and RA315 and their respective associated armatures RA313 and RA316, the relay R310 connects 20 the line conductors 305 and 306 to the opposite terminals of the repeater coil winding 341, 342. At RA313 and RC314, the relay R310 opens a point in its original operating circuit, but only after an alternative branch circuit has been completed, by way of RA313, RA312 and the winding 341, for maintaining its energized. 25

At RA311, the relay R310 completes a simplex circuit for energizing R210 located at the station 200, one branch of this circuit extending from ground at the armature noted by way of the conductor 318, the winding 343, the line conductor 205, the winding 291, the switch springs 285 and 286, RA233, the winding of R210 and the conductor 215 to battery. The other branch 30 of the simplex circuit extends from ground at RA311 by way of the conductor 318, the winding 344, the line conductor 206, the winding 292, the switch springs 285 and 286, RA233, the winding of R210 and the conductor 215 to battery. The relay R210 now operates to complete, at RA211, the above-noted alternative circuit for energizing the signal device 287, which circuit extends from ground as applied to the conductor 216 by way of RA211, the winding of the magnet 289 and 35 the springs 288 to battery. Through the circuit-interrupting action of the springs 288, the signal device 287 is caused to operate to give an audible indication that the station 200 is being called. The relay R210, upon operating, also functions 40 to complete a simplex circuit for energizing R110 embodied in the apparatus provided at the station 100. One branch of this circuit extends from ground on the conductor 217 by way of the upper winding of R230, the conductor 218, 45 RC216, RA212, the conductor 219, the switch springs 283 and 282, the winding 293, the line conductor 105, the winding 191, the switch springs 185 and 186, RA133, the winding of R110 and the conductor 115 to battery. The other 50

branch of this circuit is quite similar to that just described but extends by way of the winding 294, the line conductor 106 and the winding 192 rather than by way of the winding 293, the conductor 105 and the winding 191. Due to the relatively high resistance of the winding of R110, the relay R230 does not operate when its upper winding is energized over the above-traced circuit. The relay R110, however, operates to complete, at RA111, the above noted alternative circuit for energizing the signal device 187, this circuit extending from ground on the conductor 116 by way of RA111, the winding of the magnet 189 and the contact springs 188 to battery. Due to the circuit interrupting action of the contact springs 188, the signal device 187 operates to give an audible indication that the station 100 is being called.

Obviously, the above-described operations occur each time the push button 363 embodied in the hand set 360 is depressed. If desired, this push button may be actuated in accordance with a coded signal selectively to indicate which of the two stations 100 and 200 is being called. It may happen that the trainman who initiates the call desires to converse with the engineers in both locomotive cabs, in which case a coded signal indicating the non-selective call may be transmitted through proper manipulation of the push button 363. Following operation of the push button 363 to signal the desired station, this button is held depressed to maintain R310 operated. With this relay operated the conductors 305 and 306 of the line circuit section are maintained connected to the opposite terminals of the repeating coil winding 341, 342 and the operating circuit for R320 is held open.

Assuming, for the moment, that the call is intended for the station 200, the desired connection is established when the call is answered at this station by actuation of the button 243 embodied in the hand set 240 to move the contacts carried by the springs 244 into engagement. In response to this operation, a circuit is completed for energizing R230, this circuit extending from ground on the conductor 217 by way of the upper winding of R230, the conductor 223, the switch springs 244, the resistor 222 and the conductor 215 to battery. The resistor 222 is a current determining resistor and the value thereof is selected so that the full rated current for the upper winding of R230 is passed through this winding when the springs 244 are closed. Hence, R230 is caused to operate when energized over the above-traced circuit and, upon operating, opens, at RA233, a point in the above-traced operating circuit for R210. The relay R210 now restores to open, at RA211, the alternative operating circuit for the signal device 287. At RA212 and RC214, the relay R210 opens a point in the simplex circuit, traced above, for energizing R110, causing the last-mentioned relay to restore to open, at RA111, the alternative operating circuit for the signal device 187. Thus, it will be seen that, when the push button switch incorporated in the hand set 240 is operated, the two signal devices 187 and 287 are deenergized. At RA232, the relay R230 completes a simplex holding circuit for itself, one branch of this circuit extending from ground, at the operated armature RA311, by way of the conductor 318, the winding 343, the line conductor 205, the winding 291, the switch springs 285 and 286, RA232, the lower winding of R230 and the conductor 215 to battery. The second branch of this circuit is sub-

stantially similar to that just traced but extends by way of the winding 344, the line conductor 206 and the winding 292 rather than by way of the winding 343, the conductor 205 and the winding 291 as included in the first branch of the circuit, traced above. Thus, the relay R230 is held operated independently of the push button 243 so long as the push button 363 is held depressed.

When the relay R230 operates, it also functions to complete, at RA231, a path for connecting the transmitter 242 and receiver 241 across the line conductors 205 and 206 of the line circuit section 204, this path being more or less obvious and including the conductors 246 and 247. As thus connected, a talking circuit, comprising the line circuit sections 204, 304 and 307 and the repeating coils 340 and 370 is completed between the station 200 and the station 350.

Before describing the release of the connection and in order to give a full description of the operation of the apparatus, it will now be assumed that the call is answered at the station 100 rather than at the station 200. In this case, the push button 143 is depressed by the answering party to complete a circuit for fully energizing the upper winding of R130, this circuit extending from ground as applied to the conductor 117 by way of the upper winding of R130, the conductor 123, the switch springs 144, the resistor 122 and the conductor 115 to battery. Upon being energized over the above-traced circuit, R130 operates to open, at RA133, a point in the above-traced circuit for energizing R110, causing this last-mentioned relay to restore to interrupt, at RA111, a point in the alternative operating circuit for the signal device 187. At RA131, the relay R130 completes a path comprising the conductors 146 and 147 for connecting the transmitter 142 and the receiver 141 across the line conductors 105 and 106 of the line circuit section 104, thereby to complete a talking circuit including the section 104, the repeater 290, the section 204, the repeater 340, the section 304, the repeater 370 and the section 307, which extends between the stations 100 and 350. At RA132, the relay R130 completes a simplex circuit for energizing its lower winding in series with the upper winding of R230, one branch of this circuit extending from ground on the conductor 217 by way of the upper winding of R230, the conductor 218, RC214, RA212, the conductor 219, the switch springs 283 and 282, the winding 293, the line conductor 105, the winding 191, the switch springs 185 and 186, RA132, the lower winding of R130 and the conductor 115 to battery. The other branch of the circuit is similar to that just described, but includes the winding 294, the line conductor 106 and the winding 192 rather than the winding 293, the line conductor 104 and the winding 191. The relay R230 operates when its upper winding is energized over the above-traced circuit to interrupt, at RA233, a point in the above-traced operating circuit for R210, causing the last-mentioned relay to restore to open a point in the alternative operating circuit for the signal device 287. At RA232, the relay R230 completes the above-traced holding circuit for itself. Thus, R230 remains operated for the duration of the conversation and, in its operated position, holds the receiver 241 and the transmitter 242 connected across the conductors 205 and 206 of the line circuit section 204. Also, with this relay operated, R210

is maintained in its restored position so that the signal device 287 is prevented from ringing.

From the foregoing description it will readily be apparent that the call as initiated at the station 350 may be answered at either or both of the stations 100 and 200. If the call is simultaneously answered at each of these two stations, the relay R230 at the station 200 functions immediately to cause the restoration of R210 and the deenergization of the signal device 287, and the relay R130 at the station 100 functions to cause the immediate restoration of R110 and the deenergization of the signal device 187. The operation of each of the relays R130 and R230 causes the associated transmitter and receiver to be connected to the conductors of the line circuit.

The release of a talking connection as established in the manner described above is different depending upon which of the stations 100 and 200 is the answering station. Thus, if it be assumed that the call is answered at the station 200, the relay R230, upon operating, immediately completes the above-traced holding circuit for itself, which circuit extends from ground at RA311 of the operated relay R310. Since R310 is not deenergized until the connection is released at the station 350, the relay R230 will be held operated independently of its operating circuit. Hence, if the push button 243 is released while the push button 363 is still depressed, the transmitter 242 and the receiver 241 at the station 200 remain connected to the line circuit section 204 by virtue of the continued energization of R230. When, however, the push button 363 is released, the operating circuit for R310 is opened at the springs 364 causing this relay to restore. Upon restoring, R310 reprepares, at RA312, the operating circuit for R320; opens, at RA312 and 40 RA315 and their respective associated armatures RA313 and RA316, a point in the talking connection, as described above; and interrupts, at RA311, a point in the above-traced holding circuit for R230. If the push button 243 has been released prior to the release of the push button 363, the relay R230 now restores to disconnect, at RA321, the receiver 241 and the transmitter 242 from across the conductors 205 and 206 of the line circuit section 204. At its armature 50 RA233, the relay R230, upon restoring, reprepares the operating circuit for R210. Following this operation, the connection is entirely released and the system is in connection for further use in connection with another call.

If the call is answered at the station 100 and the answering party releases the push button 143 before the calling party releases the push button 363, the relay R130 restores to disconnect the transmitter 142 and the receiver 141 from across the conductors of the line section 104, and to reprepare, at RA133, the operating circuit for R110. Thereafter, and when the calling party releases the push button 363 to open the operating circuit for R310, this last mentioned relay restores to open a point in the talking circuit; to reprepare, at RA312, the operating circuit for R320; and to interrupt, at RA311, a point in the holding circuit for R230. The relay R230 now restores to disconnect, at RA321, the transmitter 242 and the receiver 241 from across the conductors of the line circuit section 204 and to reprepare, at RA233, the operating circuit for R210. Thus, the connection is completely released.

It will be apparent that, if the call is answered 75 at the station 100 and the calling party at the

station 350 releases the push button 363 before the answering party releases the push button 143, the order of the operations is the reverse of that just described. More specifically, when the button 363 is released, the operating circuit for R310 is interrupted at the springs 364 whereupon this relay restores to open the holding circuit for R230. Thereafter and when the push button 143 is released, the operating circuit for R130 is opened at the springs 144 and this relay restores. 10 It is apparent, therefore, that the release of the connection as established between the stations 100 and 350 is in no way affected by the order in which the push buttons 143 and 363 are released.

The operation of the apparatus following the initiation of a call at the station 300 is identical with that just described insofar as the apparatus at the stations 100 and 200 is concerned, but differs therefrom in that the apparatus at the station 350 is locked out and the apparatus at the station 300 is connected to the line circuit. Thus, when the push button 333 is depressed to initiate a call at the station 300, a circuit is completed for energizing R320, this circuit extending from ground as applied to the conductor 326 by way 25 of the switch springs 334, the conductor 327, RA312' and through the winding of R320 to battery. The relay R320 now operates and, at RA321, applies ground to the conductor 318, thereby to cause the energization and operation of 30 both of the signal devices 187 and 287 located, respectively, at the stations 100 and 200, in the exact manner set forth above. At its armatures RA322 and RA325, the relay R320 connects the conductors 328 and 329 to the respective terminals 35 of the repeater coil winding 341, 342, whereby the transmitter 332 and the receiver 331 are connected across this winding to prepare a talking circuit to one or both of the two stations 100 and 200. At RA323 and RA324 the relay R320 opens 40 points in the above-traced operating circuit for R310, whereby this relay is prevented from operating in response to actuation of the push button 363 so long as the push button 333 is held depressed. At RA323 and RA324, the conductors 45 forming the line circuit section 304 are disconnected from the repeater coil 340.

The mode of operation of the apparatus provided at the stations 100 and 200 following the initiation of a call at the station 300 is, as was 50 pointed out above, exactly the same as that set forth previously with reference to a call initiated at the station 350, and this is true irrespective of whether the call is answered at the station 100, the station 200, or both. Also, the mode of disconnecting the apparatus from the line circuit to release the equipment for further use is similar to that described above, differing therefrom only in that ground is removed from the conductor 318 to open the holding circuit for R230 following the 60 release of the push button 333 to open the operating circuit for R320. When R320 restores, it not only removes ground from the conductor 318, but also disconnects the receiver 331 and the transmitter 332 from across the winding 341, 342 65 of the repeating coil 340 and reprepares the operating circuit for R310, so that the last-mentioned relay may be energized in response to the initiation of a call at the station 350.

As indicated above, it is possible for two of the 70 train attendants to hold intercab communication in either of the two locomotive cabs. Thus, a trainman at the station 100 may initiate a call directly to the station 100, without in any way affecting the apparatus located at the other sta- 75

tions, by actuating the push button 175 of the manually operable switch comprising the springs 176. This operation serves to complete the operating circuit for the signal device 187, which circuit extends from ground as applied to the conductor 162 by way of the switch springs 176, the conductor 164, the winding of the operating magnet 189 and the contact springs 188 to battery. The resulting operation of the signal device 187 gives an audible indication that the station 100 is being called. The call is answered at the station 100 in the usual manner by depressing the push button 143 to complete the above-traced circuit for energizing the upper winding of R130. The relay R130 now operates to connect, at RA131, the receiver 141 and the transmitter 142 of the hand set 140 across the conductors 105 and 106 of the line circuit section 104. At RA133, the relay R130 opens a point in the operating circuit for R160, whereby the signal device 187 is prevented from being energized in response to the initiation of a call at one of the stations 200, 300 and 350. The connection is completed when the push button 173 embodied in the hand set 170, provided at the station 150, is depressed, this operation serving to complete a circuit for energizing R160. Specifically, this circuit extends from ground as applied to the conductor 162 by way of the switch springs 174, the conductor 163 and through the winding of R160 to battery. The relay R160, upon operating, completes, at RA161, a path comprising the conductors 177 and 178 for connecting the transmitter 172 and the receiver 171 across the line conductors 105 and 106 of the line circuit section 104.

To release a connection as established between the stations 100 and 150 in the manner set forth in the immediately preceding paragraph, it is only necessary that the two push buttons 143 and 173 be released. When the first mentioned button assumes its normal position, the operating circuit for R130 is opened, causing this relay to restore to disconnect the transmitter 142 and the receiver 141 from across the conductors of the line circuit section 104. Similarly, when the push button 173 is released, the operating circuit for R160 is interrupted at the switch springs 174, causing this relay to restore to open, at RA161, a point in the path by way of which the receiver 171 and the transmitter 172 are connected across the conductors 105 and 106.

Since, as was pointed out above, the apparatus located in the second locomotive cab is identical 55 in all respects with that provided in the first locomotive cab, it will be understood that a connection may be established between the stations 200 and 250 on a call from the latter to the former and, further, that the operations involved in completing and releasing such a connection are identical with those just described with reference to the establishment of a connection on a call from the station 150 to the station 100.

65 The initiation of a call to the station 200 located in the second locomotive cab from the station 100 located in the first locomotive cab involves the use of the non-locking key switch 180. More specifically, when this switch is operated to its off-normal position, a simplex circuit is completed for energizing R220, one branch of this circuit extending from ground on the conductor 117 by way of the switch springs 184 and 185, the winding 191, the conductor 105, the winding 293, the switch springs 282 and 283,

the conductor 219, RA212, RC213 and through the winding of R220 to battery as applied to the conductor 215. The other branch of this circuit is similar to that just described, but extends by way of the winding 192, the conductor 106, and 5 the winding 294 rather than by way of the winding 191, the conductor 105, and the winding 293. The relay R220, upon operating, completes, at RA221, the above-traced alternative operating circuit for the signal device 287, which device 10 now operates to give an audible indication that the station 200 is being called. Following operation of the switch in accordance with the coded ring identifying the station 200, this switch is released to interrupt the above-traced operating 15 circuit for R220, whereby this relay is caused to restore to open the operating circuit for the signal device 287. A talking connection is established by depressing the two push buttons 143 and 243. When the button 143 is depressed, the 20 above-traced operating circuit for R130 is completed at the switch springs 144, causing this relay to operate to complete, at RA131, the path for connecting the receiver 141 and the transmitter 142 across the conductors of the line circuit section 104. When the push button 243 embodied in the hand set 240 is depressed, the operating circuit for R230 is similarly completed at the springs 244, whereby this relay is caused to operate to complete, at RA231, the path for 30 connecting the transmitter 242 and the receiver 241 of the hand set 240 across the conductors of the line circuit section 204. So long as the two push buttons noted are held in their respective depressed positions, a talking circuit is completed between the two stations 100 and 200, which circuit specifically comprises the line circuit section 104, the repeating coil 290, and a portion of the line circuit section 204. In order to release a connection as set up in the manner just described, it 40 is only necessary for the two parties to release the two push buttons 143 and 243, thereby to open the respective operating circuits for the relays R130 and R230. When these relays restore, the transmitters and receivers embodied, respectively, in the two hand sets located at the respective stations are disconnected from the line circuit and the apparatus is in condition for further use.

The operation of the apparatus to set up a 50 talking circuit between the two stations 100 and 200 on a call from the latter to the former is, in general, quite similar to that set forth in the preceding paragraph. In this case, however, the non-locking key switch 280 is operated to its 55 off-normal position to effect operation of the signal device 187 located at the station 100. When this key switch is moved to its off-normal position, a simplex circuit is completed for energizing R110, one branch of this circuit extending 60 from ground on the conductor 217 by way of the switch springs 281 and 282, the winding 283, the line conductor 105, the winding 191, the switch springs 185 and 186, RA133, and through the winding of R110 to battery as applied to the 65 conductor 115. The other branch of this circuit is similar to that just described, but extends by way of the winding 294, the line conductor 106 and the winding 192 rather than by way of the winding 293, the conductor 105 and the winding 191. When R110 operates, it completes, at RA111, the above-traced alternative operating circuit for the signal device 187 causing this device to give an audible indication that the station 100 is being called. The talking circuit between 75

the two stations is identical with that briefly described in the preceding paragraph and is completed in the same manner, namely, through the operation of the two push buttons 143 and 243 to cause, respectively, the operation of the two relays R130 and R230. It will be noted that when R130 operates it opens, at RA133, a point in the above-traced operating circuit for R110, thereby to cause R110 to restore to prevent further operation of the signal device 187. The interruption of the talking circuit to release the apparatus is accomplished in substantially the manner described above, that is, by releasing the two push buttons 143 and 243 to cause the restoration of the two relays R130 and R230. As pointed out above, when R130 restores, the path for connecting the receiver 141 and the transmitter 142 across the conductors 105 and 106 is interrupted at RA131 and, similarly, when R230 restores, the path connecting the transmitter 242 and receiver 241 across the line conductors 205 and 206 is opened at RA231.

From the foregoing description, it will be apparent that the position of the two locomotives 25 may be transposed without in any way disrupting the operation of the system or in any way modifying its mode of operation. More specifically, the locomotive having embodied therein the apparatus illustrated in Fig. 2 may be employed as the first locomotive and the locomotive having embodied therein the apparatus illustrated in Fig. 1 may be employed as the second locomotive. In this case, however, the line circuit section 101 will effectively be connected in the line circuit 30 and the line circuit section 104 will be open-circuited in the exact manner illustrated for the section 101. Otherwise, the apparatus located at the station 200 will operate in the manner set forth above with reference to the apparatus 40 located at the station 100, whereas the apparatus at the last-mentioned station will operate in the exact manner set forth above with reference to that located at the station 200.

While there has been described what is at 45 present considered to be the preferred embodiment of the invention, it will be understood that various modifications may be made therein, and it is contemplated to cover in the appended 50 claims all such modifications as fall within the true spirit and scope of the invention.

I claim:

1. In a signalling system, a plurality of signalling stations, a line circuit interconnecting said stations, a signal device at each of certain 55 of said stations, a switch at each of said stations, means responsive to the operation of one of said switches for causing the energization of all of said signal devices, and means responsive to the operation of another of said switches for causing the deenergization of all of said signal devices.

2. In a telephone system, a plurality of telephone stations each comprising a transmitter and a receiver, a line circuit interconnecting said stations, a signal device at each of certain of 65 said stations, a switch at each of said stations, each of said switches being operative to connect the associated transmitter and receiver to said line circuit, means responsive to the operation of one of said switches for causing the 70 energization of a plurality of said signal devices, and means responsive to the operation of another of said switches for causing the deenergization of said plurality of signal devices.

3. In a telephone system, a plurality of telephone stations each comprising a transmitter

and a receiver, a line circuit interconnecting said stations, a signal device at each of certain of said stations, a switch at each of said stations, each of said switches being operative to connect the associated transmitter and receiver to said line circuit, means responsive to the operation of the switch at a particular calling one of said stations for causing the energization of all of said signal devices, and means responsive to the operation of the switch at an answering one of said stations for causing the deenergization of all of said signal devices.

4. In a telephone system, a plurality of telephone stations each comprising a transmitter and a receiver, a line circuit interconnecting said stations, a signal device at each of certain of said stations, a switch at each of said stations, means at each station responsive to the operation of the associated switch for connecting the associated transmitter and receiver to said line circuit, means responsive to the operation of the switch at a particular calling one of said stations for preventing the transmitter and receiver at a second of said stations from being connected to said line circuit, means also responsive to the 25 operation of said last-named switch for causing the energization of all of said signal devices, and means responsive to the operation of the switch at an answering one of said stations for causing the deenergization of all of said signal devices. 30

5. In a telephone system, a plurality of telephone stations each comprising a transmitter and a receiver, a line circuit interconnecting said stations, a signal device at each of certain of said stations, a switch at each of said stations, a relay 35 at one of said stations operative in response to the operation of the associated switch for connecting the associated transmitter and receiver to said line circuit, an operating circuit for said relay, means at each of the other stations controlled by the respective associated switches for connecting the respective associated transmitters and receivers to said line circuit, a lockout relay operative to open a point in said operating circuit in response to the operation of the switch 45 at a particular calling one of said stations, means responsive to the operation of said lockout relay for causing the energization of all of said signal devices, and means responsive to the operation of the switch at an answering one of said stations 50 for causing the deenergization of said signal devices.

6. In a telephone system, a plurality of telephone stations each comprising a transmitter and a receiver, a line circuit interconnecting said stations, a signal device at each of certain of said stations, a switch at each of said stations, a relay at one of said stations operative in response to the operation of the associated switch for connecting the associated transmitter and receiver 60 to said line circuit, an operating circuit for said relay, means at each of the other stations controlled by the respective associated switches for connecting the respective associated transmitters and receivers to said line circuit, a lockout relay 65 operative to open a point in said operating circuit in response to the operation of the switch at a particular calling one of said stations, a plurality of relays each associated with one of said signal devices and operative to cause the energization of the associated signal device, circuit connections over which said last-named relays are energized and including at least a portion of said line circuit, said connections being so arranged that said last-named relays are success- 70 75

- sively energized in response to the operation of said lockout relay, and means responsive to the operation of a switch at an answering one of said stations for altering said circuit connections to cause the deenergization of said plurality of relays.
7. In a telephone system a pair of telephone stations each comprising a transmitter and a receiver, a line circuit interconnecting said stations and comprising a plurality of conductors, a manually operable switch at each station, means at each station controlled by the associated switch for connecting the associated transmitter and receiver to the conductors of said line circuit, a signal device, a second manually operable switch at one of said stations, a circuit independent of said line circuit and including contacts embodied in said second switch for energizing said signal device, an alternative circuit for energizing said signal device, a relay at the other of said stations operative to complete said alternative circuit, an operating circuit for said relay, said operating circuit including at least one of said line conductors, means responsive to the operation of the switch at the other of said stations for preventing said operating circuit from being completed, a pair of additional telephone stations associated with said line circuit, a manually operable switch at each of said additional stations, the switch at one of said additional stations being operative to complete said operating circuit only when the switch at said other station is not operated, and means responsive to the operation of the switch at the other of said additional stations for completing said alternative circuit independently of the position of the switch at said other station.
8. In a telephone system, a pair of telephone stations each comprising a transmitter and a receiver, a line circuit interconnecting said stations and comprising a plurality of conductors, a relay at each station including contacts for connecting the associated transmitter and receiver to the conductors of said line, an operating circuit individual to each relay, a manually operable switch at each station for completing the operating circuit of the associated relay, a signal device at one of said stations, a second manually operable switch at the other of said stations, a circuit independent of said line circuit and including contacts embodied in said second switch for energizing said signal device, an alternative circuit for energizing said signal device, a second relay at said one station and operative to complete said alternative circuit, and means comprising the first-named relay at said one station for preventing said second relay from operating to complete said alternative circuit when the transmitter and receiver at said one station are connected to the conductors of said line circuit.
9. In a telephone system, a pair of telephone stations each comprising a transmitter and a receiver, a line circuit interconnecting said stations and comprising a plurality of conductors, a manually operable switch at each station, means at each station controlled by the associated switch for connecting the associated transmitter and receiver to the conductors of said line circuit, a signal device, a second manually operable switch at one of said stations, a circuit independent of said line circuit and including contacts embodied in said second switch for energizing said signal device, an alternative circuit for energizing said signal device, a relay at the other of said stations operative to complete said alternative circuit, an operating circuit for said relay, said operating circuit including at least one of said line conductors, means responsive to the operation of the switch at the other of said stations for preventing said operating circuit from being completed, an additional telephone station associated with said line circuit, and a switch at said additional station operable to complete said operating circuit only when the switch at said other station is not operated.
10. In a telephone system, a pair of telephone stations each comprising a transmitter and a receiver, a line circuit interconnecting said stations and comprising a plurality of conductors, a manually operable switch at each station, means at each station controlled by the associated switch for connecting the associated transmitter and receiver to the conductors of said line circuit, a signal device, a second manually operable switch at one of said stations, a circuit independent of said line circuit and including contacts embodied in said second switch for energizing said signal device, an alternative circuit for energizing said signal device, a relay at the other of said stations operative to complete said alternative circuit, an operating circuit for said relay, said operating circuit including at least one of said line conductors, means responsive to the operation of the switch at the other of said stations for preventing said operating circuit from being completed, a pair of additional telephone stations associated with said line circuit, a manually operable switch at each of said additional stations, the switch at one of said additional stations being operative to complete said operating circuit only when the switch at said other station is not operated, and means responsive to the operation of the switch at the other of said additional stations for completing said alternative circuit independently of the position of the switch at said other station.
11. In a telephone system, a pair of telephone stations each comprising a transmitter and a receiver, a line circuit interconnecting said stations and comprising a plurality of conductors, a manually operable switch at each station, means at each station controlled by the associated switch for connecting the associated transmitter and receiver to the conductors of said line circuit, a signal device, a second manually operable switch at one of said stations, a circuit independent of said line circuit and including contacts embodied in said second switch for energizing said signal device, an alternative circuit for energizing said signal device, an additional telephone station associated with said line circuit, a manually operable switch at said additional station, and means responsive to the operation of said last-named switch for completing said alternative circuit.
12. In a telephone system, a pair of telephone stations each comprising a transmitter and a receiver, a line circuit interconnecting said stations and comprising a plurality of conductors, a manually operable switch at each station, means at each station controlled by the associated switch for connecting the associated transmitter and receiver to the conductors of said line circuit, a signal device, a second manually operable switch at one of said stations, a circuit independent of said line circuit and including contacts embodied in said second switch for energizing said signal device, an alternative circuit for energizing said signal device, a relay at the other of said stations operative to complete said alternative circuit, an operating circuit for said relay, said operating circuit including at least one of said line conductors, means responsive to the operation of the switch at the other of said stations for preventing said operating circuit from being completed, an additional telephone station associated with said line circuit, a switch at said additional station, and means responsive to the operation of said last-named switch for completing said alternative circuit independently of the position of the switch at said other station.
13. In a telephone system, a telephone station

comprising, in combination, a signal device, a transmitter, a receiver and a manually operable switch, a line extending to said station and including a pair of conductors, a relay operative in response to the application of a predetermined potential to one of said conductors to cause the energization of said signal device, and means comprising a second relay operative in response to the operation of said switch for causing the deenergization of said first-named relay and for connecting said transmitter and receiver to said line.

14. In a telephone system, a telephone station comprising, in combination, a signal device, a transmitter, a receiver and a manually operable switch, a line extending to said station and including a pair of conductors, a circuit for energizing said signal device, a relay operative to complete said circuit, an operating circuit for said relay, said operating circuit, including one of the conductors of said line circuit and being adapted to be completed when a predetermined potential is applied to said one conductor, a second relay operative in response to the operation of said switch to connect said transmitter and receiver to said line, and contacts controlled by said second relay for interrupting the operating circuit for said first-named relay when said switch is operated.

15. In a telephone system, a telephone station comprising, in combination, a signal device, a transmitter, a receiver and a manually operable switch, a repeater comprising a pair of windings, a line extending to said station, said line including a pair of conductors respectively connected to the terminals of one of said windings and a pair of conductors respectively connected to the terminals of the other of said windings, means responsive to the application of a predetermined potential to one conductor of one of said pairs of conductors for causing the energization of said signal device, means responsive to the application of said predetermined potential to one conductor of the other of said pairs of conductors for also causing the energization of said signal device, and means responsive to the operation of said switch for causing the deenergization of said signal device only when energized through the operation of said first-named means.

16. In a telephone system, a telephone station comprising, in combination, a signal device, a transmitter, a receiver and a manually operable switch, a repeater comprising a pair of windings, a line extending to said station, said line including a pair of conductors respectively connected to the terminals of one of said windings and a pair of conductors respectively connected to the terminals of the other of said windings, means responsive to the application of a predetermined potential to one conductor of one of said pairs of conductors for causing the energization of said signal device, means responsive to the application of said predetermined potential to one conductor of the other of said pairs of conductors for also causing the energization of said signal device, means responsive to the operation of said switch for causing the deenergization of said signal device only when energized through the operation of said first-named means, a second manually operable switch at said station, said second switch being operative to apply said predetermined potential to one of the conductors of said one pair of conductors without causing the operation of said signal device.

17. In a telephone system, a plurality of tele-

phone stations each comprising a transmitter and a receiver, a line circuit interconnecting said stations, a signal device at each of certain of said stations, and control apparatus located at each of said stations; said control apparatus, said signal devices, and said line circuit being so connected and arranged that all of said signal devices may simultaneously be energized from certain of said stations, said signal devices may selectively be energized from others of said stations, and talking connections including said line circuit may be established between at least a portion of said telephones.

18. In a telephone system, a plurality of telephone stations each comprising a transmitter and a receiver, a line circuit interconnecting said stations, a signal device at each of certain of said stations, at least one switch at each of said stations, and control apparatus located at each of said stations; said control apparatus, said signal devices, said line circuit and said switches being so connected and arranged that all of said signal devices are simultaneously energized in response to the operation of certain of said switches, said signal devices are selectively and individually energized in response to the actuation of others of said switches, and talking connections including said line circuit may be established between at least a portion of said telephones.

19. In a telephone system for use on board a train comprising a plurality of interchangeable vehicles, a pair of telephone stations in each of certain of said vehicles, a single telephone station in each of others of said vehicles, said stations being adapted to be interconnected by a line circuit extending therebetween and each comprising a transmitter, a receiver and control apparatus; the control apparatus, the transmitter and the receiver at each of the two stations in each vehicle having a pair of stations being so connected and arranged that the positions of the vehicles having two stations may be interchanged in the train without interfering with the operation of said system.

20. A train telephone system comprising a terminal station located at one point on the train, a plurality of telephones located at other and different points on said train, a line circuit extending through the train and adapted to interconnect said telephones and said terminal station, a signal device at said terminal station, a switch associated with one of said telephones, means responsive to operation of said switch for connecting said one telephone to said line, and means also responsive to operation of said switch for causing the operation of said signal device.

21. A train telephone system comprising a terminal station located at one point on the train, a plurality of telephones located at other and different points on said train, a line circuit extending through the train and adapted to interconnect said telephones and said terminal station, a signal device at said terminal station, a switch associated with one of said telephones, means responsive to operation of said switch for energizing said signal device, and means also responsive to operation of said switch for preventing any telephone other than said one telephone from being connected to said line.

22. A train telephone system comprising a terminal station located at one point on the train, a plurality of telephones located at other and different points on said train, a line circuit extending through the train and adapted to interconnect said telephones and said terminal

- station, a signal device at said terminal station, a switch associated with one of said telephones, means responsive to operation of said switch for connecting said one telephone to said line, means 5 also responsive to operation of said switch for causing the operation of said signal device, and means also responsive to operation of said switch for preventing any telephone other than said one telephone from being connected to said line.
10. 23. In a telephone system for use in a train comprising a plurality of interchangeable vehicles, a plurality of telephone stations in each of

at least a portion of said vehicles, said stations being adapted to be interconnected by a line circuit extending therebetween and each comprising a transmitter, a receiver and control apparatus; the control apparatus, the transmitter, and the receiver at each of the stations in each vehicle having a plurality of stations being so connected and arranged that the positions of the vehicles having a plurality of stations may be interchanged without interfering with the opera- 10
5
tion of the system.

EDWARD S. PETERSON.
